No. 739,878.

PATENTED SEPT. 29, 1903.

J. JACKSON.

STATION INDICATOR.

APPLICATION FILED JUNE 16, 1903.

NO MODEL

UNITED STATES PATENT OFFICE.

JOHN JACKSON, OF GRANDCANE, LOUISIANA.

STATION-INDICATOR.

SPECIFICATION forming part of Letters Patent No. 739,878, dated September 29, 1903.

Application filed June 15, 1903. Serial No. 161,577. (No model.)

To all whom it may concern:

Be it known that I, JOHN JACKSON, a citizen of the United States, residing at Grandcane, in the parish of De Soto and State of Louisiana, have invented a new and useful Station-Indicator, of which the following is a specification.

This invention relates to that class of devices which are known generally as "station-indicators" and which are used in passenger-coaches of railways and trains for the purpose of indicating for the information of the passengers the name of the next station at which a stop is expected to be made.

My invention has for its object to produce a device of this class which shall possess superior advantages in point of simplicity, durability, and general efficiency; and with these ends in view it consists in the improved construction, arrangement, and combination of parts, which will be hereinafter fully described, and particularly pointed out in the claims.

In the accompanying drawings I have illustrated one form of embodiment of my invention; but it is to be understood that I do not limit myself to the structural details therein set forth, inasmuch as departures from the same may be made with regard to the shape, proportion, and general assemblage of parts without departing from the scope of the invention.

In said drawings, Figure 1 is a front elevation of a device constructed in accordance with the principles of my invention. Fig. 2 is a vertical sectional view taken on the line 2 2 in Fig. 1. Fig. 3 is a side elevation. Fig. 4 is a transverse sectional view taken on the line 4 4 in Fig. 2.

Corresponding parts in the several figures are indicated by similar numerals of reference.

In the form of embodiment of my invention illustrated in the drawings hereto annexed 1 designates a casing, which in this instance consists of side pieces 2 2, preferably made of wood and having curved upper and lower ends 3 3, and a front piece 4, which is preferably constructed of sheet metal and which is nailed or otherwise secured to the side pieces 2 2, as well as to the curved ends 3 of the latter, the front piece 4 being thus bent

to form the upper and lower end pieces 5 5, the extremities of which are bent to form flanges 6, through which nails, screws, or other fastening means for mounting the device in its proper position may be passed.

The front piece 4 is provided with a slot 7 in the face thereof, and behind this slot is arranged a cross-piece 8, spacing the side pieces 2 2 of the device. The cross-piece 8 should be spaced from the front piece 4 merely sufficiently to admit of the passage of the apron 9, bearing the names of the stations, as will be presently set forth.

The sides 2 2 of the casing are provided above and below the cross-piece 8 with bearings for shafts 10 and 11, carrying rollers 12 and 13, which are mounted securely upon said shafts, which latter extend through perforations in the side pieces which form the bearings. The bearings may be reinforced by metal plates, such as shown at 14, upon the inner sides of the side pieces. The rollers 12 and 13 are shorter than the distance 75 between the side pieces 2 2, and between one of said side pieces and the adjacent ends of the rollers are interposed springs 15, coiled upon the said shafts. These springs naturally tend to force the rollers in the direction 80 of the opposite side 2, where recesses 16 are provided, which are engaged by collars or washers 17 upon the ends of the roller-shafts opposite to the ends having the coiled springs. These collars or washers 17 are intended to 85 serve, in conjunction with the springs 15, to create sufficient friction to prevent the roller-shafts from being accidentally rotated. The collars or washers 17 may, as in the drawings hereto annexed, be made integral with the 90 rollers, as may be shafts of the latter.

The ends of the roller-shafts which by the action of the springs 15 are normally projected beyond the side pieces 2, in which they are journaled, are provided with winding-posts or are 95 otherwise adapted to be engaged by means of a suitable key whereby they may be rotated. Pivotally mounted upon the side of the casing through which the said roller-shafts extend is a lever 18, which is preferably made of 100 elastic material and which may be shifted so as to press either of the roller-shafts against the tension of the spring 15, thus tensionally holding it against rotation by its exercise of

additional tension against the tension of the spring 15.

The apron 9, which is wound upon the rollers 12 and 13, is attached at its ends to both 5 of said rollers. Hence by winding the apron upon one of said rollers it will be unwound from the other. Printed or otherwise inscribed upon the face of the apron in letters of sufficient size to be readily observed are 10 the names of various stations, &c., to which it may be desired to direct the attention of the passengers.

The operation of this invention will be readily understood. The device is "set" by the 15 conductor or porter of the train immediately after leaving each station by simply turning the shaft of the appropriate roller by means of a key with which the operator is provided. While the roller is being turned an inward 20 pressure should be exerted upon it by means of the key, thereby avoiding undue friction. The spring-lever 18 is normally in engagement with the projecting end of the shaft of the roller from which the apron is being unwound. 25

Having thus described my invention, I claim—

1. In a station-indicator, a casing having a slot and provided with recesses formed interiorly in one of the sides thereof, a cross-piece disposed transversely behind said slot, apron-carrying rollers journaled in the sides of the casing above and below said cross-piece, tension-springs coiled upon one end of each roller-shaft between the roller and the 35 adjacent side of the casing, and friction-collars upon the roller-shafts engaging the recesses in the opposite side of the casing. 30

2. In a station-indicator, a casing, shafts journaled in the sides of said casing, apron-carrying rollers upon said shafts, spring means for forcing said rollers in the direction of one side of the casing through which the shafts of said rollers are thus projected, and a spring-lever mounted exteriorly upon the 40 casing and adapted to engage the projecting ends of the roller-shafts. 45

In testimony that I claim the foregoing as my own I have hereto affixed my signature in the presence of two witnesses.

JOHN JACKSON.
